[57] CLAIM

The ornamental design for a lid and trim for trash receptacle, as shown and described.

DESCRIPTION

FIG. 1 is a front perspective view of a lid and trim for trash receptacle, showing my new design;

FIG. 2 is a front elevational view thereof, the back elevational view being identical thereto;

FIG. 3 is a right side elevational view thereof, the left side elevational view being identical thereto;

FIG. 4 is a top plan view thereof; and,

FIG. 5 is a bottom plan view thereof.

The broken lines shown in the drawings are for environmental purposes and form no part of the claimed design.
